UNITED STATES PATENT OFFICE.

JOSEPH F. LAMB, OF NEW BRITAIN, CONNECTICUT, ASSIGNOR TO LANDERS, FRARY & CLARK, A CORPORATION OF CONNECTICUT.

IRONING MACHINE.

Application filed December 30, 1922. Serial No. 609,992

This invention relates to ironing machines.

It is the principal object of the invention to provide an efficient ironing machine that is simple in its construction and operation; that is economical to manufacture; and that is particularly suitable for household use.

With this general object in view the invention consists in the combinations, details of construction and arrangements of parts which will first be described in connection with the accompanying drawings and then more particularly pointed out.

In the drawings,—

Fig. 1 is a view in end elevation, with parts broken away and parts in vertical section, of an ironing machine constructed in accordance with the invention;

Fig. 2 is a top plan view of the same with parts broken away and removed;

Fig. 3 is a cross sectional view taken on the line 3—3 of Fig. 2;

Fig. 4 is a sectional view taken through the gear housing;

Fig. 5 is a sectional view taken on the line 5—5 of Fig. 4; and

Fig. 6 is a sectional view taken on the broken line 6—6 of Fig. 1.

Referring to the drawings, the machine is supported by a frame of any suitable construction. As here shown as an example, the frame comprises two end A pieces 10 above which are side frame pieces 11. The A pieces 10 and the side frame pieces 11 are connected by a number of tie rods 12. In the present embodiment, journaled in bearings in the frame is a shaft 13 and mounted in this shaft is a work-supporting roll 14. As here illustrated, the roll is padded by one or more windings 15 of cloth or the like.

There is provided ironing means for cooperating with the work-supporting roll, such, for example, as an ironing shoe. Although capable of various constructions, in the exemplification shown, there is provided an ironing shoe comprising a concave ironing plate 17, curved to correspond to the curvature of the rolls, a back plate 18, and end pieces 19, arranged to enclose a heating chamber 20. This shoe is mounted, as hereinafter described, to have normally a generally vertical position at the back of the roll (see Fig. 1) and the ironing plate terminates in a curved lip 21 which aids in guiding the articles fed by the roll.

Means is provided for effecting ironing pressure between the two cooperating ironing elements. This may be accomplished by moving one element toward the other. For example, with a roll having a stationary axis, as here shown, the shoe is moved toward the roll to effect the desired pressure. Although capable of various constructions, in the embodiment illustrated, the shoe is carried by a frame mounted to reciprocate in the main frame and comprising end brackets 22 with which the shoe is connected as hereinafter described. The brackets 22 are pivotally mounted on eccentric pins 23 carried by bosses 24 on the frame ends 11, these pivotal pins being located a considerable distance below the roll so that the shoe, in its movement toward the roll has substantially a right line movement.

This movement of the shoe toward the roll may be effected in various ways, for example, by mechanism including a foot treadle and a toggle action. Although capable of various constructions, in the present embodiment, extending across the front of the machine is a foot treadle 25 supported on arms 26 hung from a cross bar or tie rod 27. Fulcrumed on this tie rod 27 and connected with the treadle is a two armed lever 28, its opposite arm being pivotally connected with a link or push rod 29. This push rod is secured to a yoke 30 pivotally associated by a pin 31 with a toggle mechanism. As here shown, this toggle comprises a yoked member 32 having a hub 33 mounted on a cross rod 34 carried by the frame. Also forming part of the toggle is a link 35 mounted on the pin 31, its other end being pivotally connected by pin 36 with a yoked rocker arm 37. This rocker arm is secured to a rock shaft 38 journaled in the frame. Also mounted on the rock shaft 38, near the ends thereof, are two yoked levers 39. To provide a yieldable operating connection between each lever 39 and the shoe, as here illustrated as an example, pivoted within the yokes of levers 39 are heads 40 through which pass bolts 41. These bolts are threaded into heads 42 mounted on a part of the shoe unit. In the present embodiment, they are mounted on a heating pipe 43 which extends through the shoe as hereinafter more fully referred to, and is supported in the brackets 22, thus

forming part of and moving with the shoe unit. Between the heads 42 and the heads 40 are springs 44.

When the foot treadle is depressed, 5 through the toggle mechanism and connections described, the levers 39 are rocked to move the heads 40 toward the roll and the actuating force is transferred to the shoe unit through the springs 44. The shoe unit, 10 however, can yield when necessary against the springs, bolts 41 sliding in the heads 40. Bolt heads 45 hold the bolts in normal position in the heads. The shoe unit will thus be moved from the full line position of Fig. 15 1 to some such position as that shown in dotted lines, the extent of shoe movement toward the roll depending on the pressure desired and the thickness of goods to be ironed and being controlled by the treadle.

20 Means is provided for tending to separate the shoe from the roll. While this may be accomplished by various constructions, as here shown as an example, a coil spring 46 is connected at one end to the pivot pin 36 and 25 at the other end to a frame brace 47. With this construction, operation of the toggle in moving the shoe toward the roll distends the spring and the spring thus tends to break the toggle and hold the shoe in open or released position.

The invention includes means for locking the shoe in a plurality of pressing positions and this may be accomplished, for example, by a dog and ratchet mechanism. Although 35 capable of various constructions, in that here illustrated, integral with the hub of the toggle member 32 is a toothed sector 48 forming a ratchet. Cooperating with the ratchet teeth is a dog 49 mounted on a rock shaft 40 50 journaled in the frame, the dog being held to its duty as later described. As the toggle member 32 swings upwardly the ratchet 48 swings downwardly, retrograde movement being prevented by the engagement 45 of the ratchet teeth with the dog. With this construction the shoe is locked in the various positions to which it may be moved and the operator is relieved of the necessity of holding the treadle depressed to maintain 50 ironing pressure.

The invention in its entirety includes means for releasing the locking means to permit the shoe to withdraw under the force of its return spring and in structures embodying the invention to the best advantage the releasing means is manually operable and may include a release lever accessible above the work table. Although capable of various constructions, in the present embodiment, 60 mounted on the rock shaft 50, near the right hand end of the machine, is a rocker arm 51 pivotally connected to a link 52, which, in turn, is pivoted to a bell crank lever 53 pinned to the frame. The free arm of this 65 bell crank extends through a slot 54 in a

work table 55 supported on the frame, and terminates in a handle 56. To hold the parts in normal position with the dog 49 held to its duty, a spring 57 connects the bell crank 53 with the frame.

70 With the construction described, the shoe may be easily and substantially instantaneously released from the roll. Operation of the handle 56, which is readily accessible above the work table where the operator's hands are ordinarily located, rocks the shaft 50 to release the locking dog 49 from the ratchet. This permits the spring 46 to cause separation of the shoe from the roll as described. Normal position of the parts is 80 controlled, in the present embodiment, by a stop 58 carried by the ratchet and engaging the under side of the dog as shown in Fig. 1.

85 The invention in its entirety includes the provision of manually operable means for releasing the locking means, accessible at each end of the work table. This may be accomplished, for example, in connection with the release lever 56 already described, 90 by a second release lever at the left end of the machine, this second release lever being accessible to an operator either at the front or end of the machine. Although capable of various constructions, as here shown as an 95 example, mounted on the rock shaft 50 near the left end of the machine is a rocker arm 59 pivoted to a link 60, in turn pivoted to a hand lever 61 which is pinned to the frame just below the work table and extends forward beyond the edge thereof. With this construction, the locking dog may be released by a hand lever accessible to an operator working either at the front of the machine or at the left end.

100 The invention in its entirety includes a pivotal mounting for the ironing shoe, whereby the shoe may be swung away from the roll to expose its concave ironing surface, and in structures embodying the invention 110 to the best advantage the pivotal mounting includes a heating conduit. Although capable of various constructions, as here shown as an example, each end piece 19 of the shoe is formed with a boss 62 through which extends the heating conduit 43 before referred to. A bushing 63 may be provided if desired. The pipe 43 also extends through bosses 64 formed on the brackets 22 and is thus supported by the brackets and forms 120 part of the shoe unit.

125 Means is provided for normally latching the shoe to the brackets 22 whereby brackets and shoe constitute a unit. Although capable of various constructions, in the present embodiment, above the pivotal mounting of the shoe, the end plates 19 have socketed bosses 65 for receiving latching pins 66. These pins are slidable in bosses 67 on the brackets 22 and extend into housings 68. 130

Within the housing are springs 69 for normally forcing the pins 66 outwardly to hold them in latching position in the shoe sockets. On the ends of the pins are knobs or handles 70 by which the pins may be withdrawn when it is desired to open the shoe for cleaning or the like.

With the construction described the shoe can be swung from the normal vertical position of Fig. 1 to the horizontal position of Fig. 3 and in the latter position the concave ironing plate 17 is readily and wholly accessible for cleaning or the like. A shoulder 71 on each bracket serves as a stop and support for the shoe in this open position. It is noted also that this movement of the shoe interferes in no way with the heat supply system. Furthermore, the pipe 43 and the pins 66 constitute a two-point connection between each end of the shoe and the corresponding bracket so that brackets and shoe form a firm and solid unit for the normal pressing and release movement of the shoe.

As shown in the present embodiment, the faces of bosses 67 are corrugated as indicated at 72, thus reducing the loss of heat from the shoe by conduction.

There is provided means for rotating the work-supporting roll with varying speed so that different speeds may be obtained in accordance with variation in shoe pressure. Although capable of various constructions, as here illustrated as an example, the shaft 13 extends beyond the right hand frame bearing, as shown in Fig. 4, and enters a gear housing 81 carried by the frame. Keyed to shaft 13 and slidably thereon, is a clutch member 82 having clutch pins 83 on each face. Cooperating with these clutch pins 83 are sockets 84 formed in gears 85 and 86 journaled on the shaft 13. Gears 85, 86 mesh, respectively, with pinions 87, 88 keyed to a counter shaft 89. Also keyed to counter shaft 89 is a gear 90 meshing with a pinion 91 rotating with a sleeve 92, which is driven by a worm gear 93 meshing with a worm 94 on a power shaft 95. This power shaft may be driven in any suitable manner, as by an electric motor 96 carried by the frame.

The clutch member 82 in the present embodiment, is shifted by means of a yoke 97 connected thereto, the yoke being operated by a rock shaft 98 to which is secured a controller handle 99 located on top of the transmission housing. The controller handle is releasably held in neutral position by means of a spring pressed ball 100, which engages a corresponding socket in the top of the gear housing.

With the construction described, while the motor is running the gears 85, 86 are rotating. When the controller handle is in central or neutral position, the clutch mem-

ber is between the gears 85, 86 and idle. When the controller is moved to right or left the clutch engages one or the other of gears 85, 86 and is driven thereby, thus driving shaft 13 and the roll. It will be seen that the gearing referred to is designed to give two different speeds for the shaft 13, so that the speed may be varied, if desired, with variations in ironing pressure.

The ironing shoe may be heated in various ways. In the present embodiment the heating conduit 43 is a gas pipe provided with burner openings 101 at intervals along the pipe. At one end of the pipe there is provided an air and gas mixing device 102 of any suitable construction, and adapted for connection with a source of gas. The back plate 18 of the shoe is provided with bottom air openings 103 and top air openings 104. Above the latter, in the present embodiment, are reflectors 105 arranged, as more clearly appears in Fig. 1, to direct the heated air from the shoe backwards and so away from the operator.

There is provided a removable work receiving table arranged to be readily positioned below the ironing elements. As here shown as an example, a substantially flat work-receiving table 106 is provided, the rear edge being curved upwardly as shown in Fig. 3 to aid in guiding the work. This table is arranged to be supported by resting on the front and rear tie rods 12. To hold the table in position, in the present embodiment, extending downwardly from the table 106 are lugs 107 spaced to engage the inner surfaces of the tie rods as appears in Fig. 3. With this construction the table is held in place but is easily removed for cleaning or the like, when desired.

The operation of the machine will be clear from the above description.

What is claimed is:

1. In an ironing machine, in combination, a frame, a work-supporting roll, an ironing shoe having a concave surface for cooperating with said roll, a bracket at each end of the shoe movably mounted in the frame, the shoe being pivotally movable with respect to the brackets, a heating conduit about which the shoe pivots, and means for releasably latching the shoe to said brackets to form a unit therewith.

2. In an ironing machine, in combination, a frame, a work-supporting roll, an ironing shoe having a concave surface for cooperating with said roll, a bracket at each end of the shoe pivoted to the frame, the shoe being pivotally movable with respect to the brackets, a pin on each of said brackets, and sockets in the shoe for receiving said pins, whereby the shoe may be latched to the brackets to move therewith and released from the brackets to swing on its pivot.

3. In an ironing machine, in combination,

a work-supporting roll, an ironing shoe co-operating therewith, means for supplying heat to the shoe, a frame, a bracket movably mounted in said frame, a pivotal 5 mounting for the shoe whereby the shoe may swing with respect to said bracket, a latching pin carried by the bracket, a socket in the shoe for receiving said pin, and a boss on the bracket, through which said pin projects, having a corrugated face, thereby to 10 aid in insulating the shoe.

4. In an ironing machine, and in combination, a work-supporting roll, an ironing shoe having a concave surface for co-operating 15 with said roll, a pair of bracket arms normally extending alongside the ends of the shoe, a frame, pivot pins associated with the frame below the shoe for pivotally mounting the bracket arms in the frame, a 20 pivot element associated with said brackets and on which the shoe is pivotally mounted, and means for latching the ends of the shoe to said bracket arms.

5. In an ironing machine, and in combination, two cooperating ironing elements, 25

a foot treadle, a push rod operated thereby, a toggle mechanism operated by said push rod, a toothed sector moving with said toggle mechanism, a connection between the toggle mechanism and one of said ironing 30 elements for moving the latter upon operation of the toggle, a spring tending to break the toggle, and releasable locking means including a dog cooperating with said toothed 35 sector.

6. In an ironing machine, and in combination, two cooperating ironing elements, a foot treadle, a push rod operated thereby, a toggle mechanism operated by said push rod and having one member provided with 40 a pivotally mounted hub, a connection between the other toggle member and one of said ironing elements, a spring tending to break the toggle, a toothed segment connected with said hub, and releasable locking means including a dog cooperating with 45 said toothed sector.

In testimony whereof, I have hereunto set my hand.

JOSEPH F. LAMB.
